UNITED STATES PATENT OFFICE.

ENOCH T. FERNBRENN, OF TOLEDO, OHIO, ASSIGNOR TO THE LIBBEY-OWENS SHEET GLASS COMPANY, OF TOLEDO, OHIO, A CORPORATION OF OHIO.

APPARATUS FOR CUTTING SHEET GLASS.

Application filed March 31, 1924. Serial No. 703,032.

To all whom it may concern:

Be it known that I, ENOCH T. FERNBRENN, a citizen of Sweden, residing at Toledo, in the county of Lucas and State of Ohio, have invented new and useful Improvements in Apparatus for Cutting Sheet Glass, of which the following is a specification.

This invention relates to the art of making continuous sheet glass, and more particularly to an improved mechanism for cutting or scoring the moving sheet longitudinally after it has been formed and annealed.

In certain processes for producing sheet glass, the sheet is drawn in the form of a long continuous strip or ribbon which is passed through a horizontal leer or annealing oven, from which it emerges onto a moving conveyor or cutting table where the strip is divided transversely into sections of suitable size. The edge portions of the continuous glass strip or ribbon are usually somewhat thicker than the main central portion, and these edges are often roughened or marred by the width-maintaining mechanism through which these edge portions pass adjacent the sheet source. It is necessary to remove these edge strips, and for this purpose scoring tools have been provided which are yieldably held in engagement with the upper surfaces of the moving sheet, adjacent its edges, shortly after the sheet emerges from the leer and passes onto the cutting table. These mechanisms make continuous score lines adjacent the sheet edges whereby these sheet edges may be broken away. A type of mechanism for this purpose now in use is disclosed in the patent to Deputy, 1,407,736, granted February 28, 1922.

These scoring mechanisms bear with a constant pressure upon the upper surface of the sheet at points adjacent its edges, whereas there is no corresponding pressure upon the intervening central portions of the sheet. Ordinarily this unequal pressure will not have any injurious effect, but very often when the sheet is scored transversely, at points in advance of these edge scoring mechanisms, and then lifted somewhat beneath this transverse score line to break the sheet at that point, this lifting force which is resisted only at the two edge points by the downward pressure of the edge-scoring devices and not at any point across the

central portion of the sheet will often cause breakage, the line of cleavage running off from the transverse scored line at an angle usually away from one of the sheet edge scoring mechanisms and breaking a large corner section from the cut sheet. Similar breakage may also be caused when the glass sheet is warped, or not as flat as should normally be the case.

The cutting mechanism here disclosed is designed to avoid these breakage losses. According to this invention the scoring tools which bear with a constant yielding pressure against the upper surface of the sheet near its edges are opposed beneath the sheet by a movable supporting means, the tool carrier and supporting means both being mounted on the same balanced carrier whereby they may ride bodily and in unison up and down with the glass sheet as it is moved from its normal horizontal plane without exerting any additional pressure on the sheet edge, beyond the normal yielding pressure grip of the cutting tool and its opposing means which remains constant. Means are also provided for adjusting the scoring tools and the corresponding sheet supporting means in and out with relation to the sheet edge for removing strips of any desired width from the continuous sheet or ribbon. These adjusting means for the cutters at both sides of the sheet may all be manipulated from that side of the machine where the cutter or operator will normally be stationed.

The objects and advantages of this invention will be more apparent from the following detailed description of one approved form of the mechanism, embodying the principles of this invention.

In the accompanying drawings:

Fig. 1 is an elevation of the scoring mechanism, the glass sheet and cutting table being shown in transverse vertical section.

Fig. 2 is an end view of one of the cutting mechanisms, this view being taken substantially on the line 2-2 of Fig. 1.

Fig. 3 is a similar view of the cutting mechanism for the other edge of the sheet, this view being taken on the line 3-3 of Fig. 1.

Fig. 4 is an enlarged section through part of one of the cutter supporting means.

At 1 is shown the end of the leer or annealing oven from which the glass sheet 2

emerges onto the cutting table or conveyor 3. As here shown this conveyor 3 consists of a series of parallel endless chains or belts, each comprising a series of wooden sheet 5 supporting blocks 4, and a series of rollers 5 traveling along fixed rails or guides 6 beneath the table. It will be understood that this table and the glass sheet are considerably wider than indicated in Fig. 1, a 10 portion of the table and other mechanism being broken away through the center of this figure. The sheet supporting conveyor or table just described is not as wide as the glass sheet 2, and the edge portions of this 15 sheet are usually supported upon a pair of fixed wooden rails throughout the greater portion of their travel. These rails do not extend clear up to the leier-end of the cutting table and are not shown in the present 20 drawings.

A continuous shaft 7 extends above the path of travel of sheet 2 at right angles to the direction of the sheet's movement, and is mounted at its ends in fixed standards 8 25 carried by a fixed portion 9 of the supporting framework for the cutting table. The scoring mechanisms now to be described are mounted to swing bodily about this shaft 7, which serves as an axis of oscillation for 30 the main portions of these mechanisms.

The scoring mechanism at the right-hand side of the machine, as seen in Fig. 1, will first be described. This is the side of the machine at which the cutter or operator 35 will normally be stationed. Rotatably mounted on shaft 7 adjacent this end of the shaft is a carrier 10 comprising a central hub pivoted on the shaft, an upwardly extending bracket arm 11 and a downwardly 40 extending bracket arm 12. A sleeve 13 freely rotatable on shaft 7 connects hub 10 with a similar hub 14 of a second carrier member having an upwardly extending bracket arm 15 corresponding to the arm 11 previously described. A supporting 45 shaft 16 is rotatably mounted in the outer ends of the bracket arms 11 and 15, parallel to the shaft 7 and sleeve 13.

Slidable longitudinally on shaft 16 is the 50 cutter-carrying member 17. Although this member may be moved longitudinally of shaft 16, it is prevented from rotation thereon by the key 18 engaging corresponding keyways in the shaft 16 and member 17. The carrier 17 may be fixed at any desired 55 location on shaft 16 by means of set-screw 19 which may readily be manipulated by the handle 20. A cutter-carrying arm 21 is pivoted at 22 in the supporting member 17, and a compression spring 23 bearing at one 60 end against the arm 21 and at the other against an adjusting nut 24 on a screw rod 25 which extends through the spring and 65 is secured at its other end 26 to member 17, holds the arm 21 yieldingly down toward

the supporting member 17. At its lower end arm 21 is adapted to support the scoring tool 27 which may be of any approved type. This scoring tool is held in the lower arm 21 by set-screw 28 whereby the tool may be 70 removed and renewed whenever found necessary. By adjusting the compression of spring 23, the scoring tool may be held down against the upper surface of glass sheet 2 with any desired pressure. The supporting 75 shaft 16 will normally be held against rotation by means hereinafter described so that the angular position of the tool supporting members just described will remain fixed. However, mechanism is provided as 80 hereinafter described for rotating the shaft 16 when desired to bodily lift the scoring tool and its supporting members away from the sheet.

Rotatably mounted in the lower bracket arm 12 of carrier 10 is a third supporting shaft 29 also parallel with the shafts 7 and 16 previously described. A bracket arm 30 is slidably supported on this shaft 29 in much the same manner as the carrier 17 is mounted on shaft 16, as described hereinabove. The bracket arm 30 is held in any desired position longitudinally of shaft 29 by the adjusting screw 31. At the outer end of supporting bracket 30 is carried a supporting roller or rollers 32 which bear up against and support the glass sheet 2 directly beneath the scoring tool 27.

Secured to the outer end of shaft 29 as 100 by means of set-screw 33, is a crank-arm 34 having a longitudinal slot 35 adjacent its upper end. A bell-crank 36 has a pin 37 at the end of one arm 38, this pin sliding in the slot 35 of crank 34. The other arm 39 of the bell-crank serves as an operating handle. Pivoted to the extreme upper end 40 of crank 34 is a link 41 having a slot 42 therein which fits over and slidably grasps a flattened extension 43 on the end 105 of shaft 16.

With the parts in the position shown in Fig. 2, which is the normal operating position, the arm 38 of the bell-crank is substantially at right angles to crank 34, with the pin 37 in the upper end of slot 35, this serving to lock the crank 34 in the position shown with relation to carrier 10 and hold the supporting rollers 32 up against the lower surface of glass sheet 2. At the same time since crank 34 is locked in position with relation to carrier 10, the link 41 will also be held in fixed position and will hold the shaft 16 against rotary movement in the upper supporting arms 11 and 15 of the carrier. Accordingly the tool supporting parts will be held in fixed position previously described with the scoring tool 27 held yieldingly against the upper surface of sheet 2 in opposition to the supporting rollers 32 therebeneath. The entire mechanism will 115 120 125 130

be substantially balanced about the axis of shaft 7, so that none of the weight of the parts will be supported by glass sheet 2. If this balance is not exact it might be preferable to have the supporting rollers 32 exert a slight preponderance of upward pressure against the lower surface of the sheet.

If at any time it is desired to remove the cutting mechanism from the sheet it is only necessary to swing the operating handle 39 in a clockwise direction as viewed in Fig. 2. This will move the pin 37 down along the slot 35 and rotate the crank-arm 34, shaft 29 and bracket 30 to swing the supporting rollers 32 downwardly away from the glass sheet. At the same time the movement of the upper end of crank 34 will swing the link 41 in such a manner as to rotate shaft 16 and lift the cutting tool upwardly away from the upper surface of the sheet. The cutting mechanism for the opposite side of the sheet is shown in this position in Fig. 3. By a reverse, or a counterclockwise motion of handle 39, the scoring tool and supporting rollers may again be returned to their operating position as shown in Fig. 2.

Since the supporting shaft 29 for the rollers 32 must extend inwardly for a considerable distance beneath the sheet edge, it is desirable to provide an additional support for its inner end. This support must be so designed as to interfere as little as possible with the balanced operation of the scoring mechanism as described hereinabove. The inner end of shaft 29, as well as the outer end adjacent the bracket 12, are rotatably mounted in a pair of similar crank-arms 44 fixed to the ends of horizontal shaft 45. Shaft 45 is pivotally mounted, parallel to shaft 29, in the upper arms 46 and 47 of a bell-crank lever mechanism pivoted at 48 to the lower supporting framework of the table. The lower end 49 of the bell-crank bears against a compression spring 50. The compression spring 50 may normally exert no pressure on the mechanism, but merely resist any abnormal tendency to depress the supporting rollers 32. Or the spring 50 may be adjusted to counterbalance a portion of the leverage mechanism. The parallel-link mechanism just described will serve as a support for the inner end of shaft 29 and at the same time will not interfere with its free swinging movement about the axis of shaft 7.

The greater portion of the cutting mechanism at the opposite edge of the sheet is exactly similar to that just described, and reference will be made only to those portions which differ from the first described mechanism. Secured as at 51 to the left-hand end of supporting shaft 7 is a crank-arm 52 having a pin 53 operating in a slot in crank-arm 54 which corresponds to the arm 34 pre-

viously described. By manipulating a crank handle 55 at the right-hand end of shaft 7 the scoring tool and the sheet-supporting rollers may be moved into or out of engagement with glass sheet 2 in exactly the same manner as described in connection with the right-hand cutting mechanism.

The left-hand cutter carrier member 17 is provided with an upper extension 55' having a slot 56, through which extends one end 75 of a push rod 57, having collars 58 at either side of member 55. This rod 57 extends transversely of the table and has a handle 59 at its right-hand end. By pushing rod 57 in or out of the left-hand carrier member 17 and the scoring tool 27 carried thereby may be moved in or out with relation to the left-hand edge of sheet 2. The cutter is held in adjusted position by a set-screw 60, mounted in bearing 61 through which the push rod 57 slides adjacent its right-hand end, as shown in Fig. 2. The slot 56 in the upper portion 55' of carrier 17 permits this carrier to be swung up and down with relation to rod 57 during the operation of raising and lowering the cutting tool 27.

A push rod 62 extending transversely beneath the cutting table and slidably mounted in bearings 63, has fork 64 at its left-hand end engaging the sides of bracket arm 30 for supporting rollers 32. By moving the push rod 62 transversely of the machine the supporting rollers 32 may be moved in or out beneath the left-hand edge of the sheet. They are held in adjusted position by set-screw 65 adjacent the right-hand end of push rod 62.

With the mechanism operating as above described it will be seen that the two scoring tools 27 will yieldably bear, independently of one another, upon the respective edge portions of the sheet with a pressure sufficient to cut the score line thereon. At the same time either scoring tool and the sheet-supporting rollers may ride up or down in accordance with any vertical movement of that portion of the sheet and thus avoid exerting any undue pressure on the edge portion of the sheet which might cause breakage. Either cutting tool and its corresponding sheet-supporting rollers can be removed from the sheet when desired by manipulating either of the handles 39 or 55 which are conveniently arranged adjacent the operator's working station. Also either tool and its supporting rollers may be adjusted in or out with relation to the sheet edge to vary the width of the strip removed from the sheet without it being necessary for the workman to go around to the opposite side of the machine.

Claims:

1. In combination with means for feeding a sheet of glass longitudinally, a sheet scoring mechanism comprising a cutter member, a cutter-carrying arm, means for holding the

cutter yieldingly against the sheet, means supporting the opposite face of the sheet, and a carrier for the arm and supporting means adapted to move with the sheet at 5 right-angles to its direction of travel.

2. In combination with means for feeding a sheet of glass longitudinally, a sheet scoring mechanism comprising a cutter member, a cutter-carrying arm, means for holding the 10 cutter yieldingly against the sheet, means supporting the opposite face of the sheet, and a carrier for the arm and supporting means pivoted to swing in a plane perpendicular to the sheet.

15 3. In combination with means for feeding a sheet of glass longitudinally, a sheet scoring mechanism comprising a cutter member, a cutter-carrying arm, means for holding the cutter yieldingly against the sheet, means 20 supporting the opposite face of the sheet, and a carrier for the arm and supporting means pivoted to swing about an axis parallel to the sheet and transverse to its direction of travel.

25 4. In combination with means for feeding a sheet of glass longitudinally, a sheet scoring mechanism comprising a cutter member, a cutter-carrying arm, means for holding the cutter yieldingly against the sheet, means 30 supporting the opposite face of the sheet, a carrier for the arm and supporting means adapted to move with the sheet at right-angles to its direction of travel, and means for simultaneously throwing the scoring device and supporting means into or out of 35 operating contact with the sheet.

5. In combination with means for feeding a sheet of glass longitudinally, a sheet scoring mechanism comprising a cutter member, 40 a cutter-carrying arm, means for holding the cutter yieldingly against the sheet, means supporting the opposite face of the sheet, a carrier for the arm and supporting means adapted to move with the sheet at right-

angles to its direction of travel, means for 45 adjusting the scoring device transversely to the sheet, and means for simultaneously throwing the scoring device and supporting means into or out of operating contact with the sheet. 50

6. In combination with means for feeding a sheet of glass longitudinally, a sheet scoring mechanism comprising a cutter member, a pivotally mounted carrier, a cutter-carrying arm pivoted on the carrier and normally 55 engaging one face of the sheet, and a supporting roller pivoted on the carrier and normally engaging the other face of the sheet opposite the cutter.

7. In combination with means for feeding 60 a sheet of glass longitudinally, a sheet scoring mechanism comprising a cutter member, a pivotally mounted carrier, a cutter-carrying arm pivoted on the carrier and normally 65 engaging one face of the sheet, a supporting roller pivoted on the carrier and normally engaging the other face of the sheet opposite the cutter, and means for holding the cutter and roller in working engagement with the sheet or simultaneously moving them out of 70 engagement.

8. In combination with means for feeding a sheet of glass longitudinally, a sheet scoring mechanism comprising a cutter member, a pivotally mounted carrier, a cutter-carrying arm pivoted on the carrier and normally 75 engaging one face of the sheet, a supporting roller pivoted on the carrier and normally engaging the other face of the sheet opposite the cutter, and lever mechanism adapted 80 to either lock the cutter and roller in working engagement with the sheet, or to throw them out of engagement.

Signed at Toledo, in the county of Lucas and State of Ohio, this 27th day of March, 85 1924.

ENOCH T. FERNBRENNER.
